UNITED STATES PATENT OFFICE.

FREDERIC PAYSON REED, OF EAST ORANGE, NEW JERSEY, ASSIGNOR, BY MESNE
ASSIGNMENTS, TO CHARLES C. ORCUTT.

COATING PAPER.

Original application filed February 6, 1920, Serial No. 356,669. Divided and this application filed September 28, 1921. Serial No. 503,871.

To all whom it may concern:

Be it known that I, FREDERIC PAYSON REED, a citizen of the United States, residing at East Orange, in the county of Essex, 5 State of New Jersey, have invented certain new and useful Improvements in Coating Paper; and I do hereby declare the following to be a full, clear, and exact description of the invention, such as will enable others 10 skilled in the art to which it appertains to make and use the same.

My invention is an improvement in paper drying machines, and relates particularly to a construction of dryer unit, adapted for use with Fourdrinier or other paper making apparatus to supplant the bulky and expensive drying rolls now used with such machines. In the usual paper making machine, the paper passes from a series of 15 press rolls to a drying apparatus, consisting of a large number of steam heated cylinders, sometimes thirty or more, carrying a felt belt or apron, which supports the paper and which separates the paper from the source 20 of heat with a solid damp belt, through which, by conduction, the heat passes to the paper. In my prior application, Serial No. 356,669, filed February 6, 1920, of which this is a division, a construction of dryer is shown 25 and described, wherein the paper moves with, and is supported by an endless belt of foraminous material, as for instance wire cloth, and a metal plate is arranged below the run of the belt supporting the paper, and 30 between the same and the source of heat. With this arrangement, the paper receives the heat more effectively, and a higher temperature can be used without danger of 35 scorching or charring the paper, because of the free circulation of air between the paper and the hot plates. A plurality of 40 sources of heat is provided, either in the form of gas jets, or electrically controlled heating units, and the said sources are distributed beneath the hot plates. Obviously 45 those portions of the plates directly above the units will be heated to higher temperatures than the portions between the same, and the distribution of the paper to be dried 50 will not be exactly uniform. Some portions of the paper will be subjected to a higher temperature than other portions, so that the drying will not be uniform throughout the sheet. While such variations in distribu-

tion are of a minor character, and of slight 55 importance with the usual grades of paper, in some grades, and especially in heavy stock, the variations may be of importance.

In the present application, I provide means arranged between the heating means 60 and the foraminous belt, and constantly changing position with respect to the heating means, whereby every part of the said means will be uniformly heated and will distribute the heat uniformly to the paper. 65

In the drawings:

Figure 1 is a side elevation of the improved unit.

Figure 2 is a detail showing the connection between the belts.

The improved heating unit comprises a suitable supporting frame 3 having at its top 4, and at each end thereof, brackets 5, which support guide rolls 6 for carrying the foraminous belt or apron 7. The upper 75 run of this belt 7, which is an endless belt, stretches between the rolls 6 beforementioned, and is supported at intervals by rolls 11, which are journaled in brackets 9, extending upwardly from the frame top 4. 80 Below the frame top, and at each end thereof, the belt passes beneath counter-weighted tension rolls 16. These rolls are journaled in arms 18 extending outwardly from the frame 3, the arms being pivoted to the 85 frame, and being counter-weighted as shown, by weights 19 in such manner as to hold the belt under a predetermined tension. A series of heaters 20 is arranged beneath the upper run of the belt, between 90 the rolls 6, and between the rolls 11, the said heaters being of any suitable character, as for instance gas jets, or electrically controlled heating units.

The foraminous belt is composed of wire 95 netting or woven wire cloth, formed of wires of any suitable cross-section, and of moisture and corrosion resisting material not distorted by heat. The said belt has air spaces as large as possible, consistent with a 100 firmly made mesh. In the present instance the belt comprises a single web of netting of somewhat greater width than the paper to be handled, and maintained by the tension rolls in a taut condition. In my above mentioned application, fixed hot plates are arranged between the heating means and the foraminous belt. In the present construc-

- tion however, I dispense with the fixed hot plates, replacing such plates by a thin flexible sheet metal belt 21 secured to the foraminous belt in any suitable manner.
- 5 Care should be observed that the materials of the screen belt and the sheet metal belt are of the same coefficient of expansion, so that there will be no puckering of the screen above the belt. With this
- 10 construction, since the metal plate travels with the screen belt, it will be uniformly heated, throughout every part thereof, the said belt constantly changing position with respect to the heating means, so that every
- 15 part thereof is subjected to the action of said means.
- The paper to be dried passes from the last press of the Fourdrinier or like machine, not shown, on to the foraminous portion of the belt, at one end of the unit. The belt moves with the web of paper, and it may be positively driven if desired, to travel at the same speed as the belt, the driving means being applied to one or both of the rolls 6.
- 20 One or more dryer units may be used according to conditions, and from the last unit,
- 25

the paper passes to the winding roll. The term screen, used herein, is intended to include all constructions of similar formation capable of performing the functions hereinbefore described, whether they be foraminous, perforate or of like formation, and of metal or any other material, in the form of wire or the like.

I claim:

1. In a drying apparatus, a source of heat, a movable hot plate heated thereby, a screen belt thereover, connections between said hot plate and said screen belt, and driving means for moving said hot plate and 40 said screen belt over said source of heat.

2. In a drying apparatus, a source of heat, a movable hot plate, a screen belt consisting of parts separated from each other through which air may pass freely, connections joining said hot plate and said screen, and driving and supporting means for moving the hot plate and the screen belt together over the source of heat.

In testimony whereof I affix my signature. 50

FREDERIC PAYSON REED.
